UNITED STATES PATENT OFFICE.

ROSS G. GRAHAM, OF SWANTON, OHIO, ASSIGNOR TO THE PILLIOD COMPANY, OF SWANTON, OHIO, A CORPORATION OF OHIO.

VALVE-GEAR.

1,219,549.

Specification of Letters Patent. Patented Mar. 20, 1917.

Application filed July 17, 1916. Serial No. 109,751.

To all whom it may concern:

Be it known that I, Ross G. GRAHAM, a citizen of the United States, and a resident of Swanton, in the county of Fulton and State of Ohio, have invented a certain new and useful Valve-Gear; and I do hereby declare the following to be a full, clear, and exact description of the invention, such as will enable others skilled in the art to which it appertains to make and use the same, reference being had to the accompanying drawings, and to the characters of reference marked thereon, which form a part of this specification.

15 This invention relates to locomotives, and particularly to valve gears for use on locomotives of the compound Mallet type, but is not restricted to use in connection with such type of locomotives.

20 It has been found in practice that for efficiency and ideal running and operating conditions with engines of the type described it is desirable for starting or slow running to admit steam in such proportion to the high

25 and low pressure cylinders that the high pressure cylinder is then the stronger, and for fast running to admit steam to the cylinders in such proportion that the low pressure cylinder is then the stronger. In practice means for obtaining these reverse or two conditions has not been present in a single locomotive, so that a locomotive adapted for slow running and heavy pulling was not adapted for fast running, and vice versa.

30 The object of my invention is to combine in a single mechanism means for obtaining these two ideal running conditions so that a locomotive equipped therewith will be adapted for both slow and fast running, thereby enhancing the efficiency and materially broadening the range of use of locomotives of the character described.

The invention is fully described in the following specification, and while, in its broader aspect, it is capable of embodiment in numerous forms, a preferred embodiment thereof is illustrated in the accompanying drawings in connection with a valve gear of the Baker type, in which drawings—

50 Figure 1 is a side elevation of a Mallet

type of engine embodying my invention. Fig. 2 is a side elevation of the front truck and low pressure cylinder with the associated valve gear. Fig. 3 is a side elevation of the rear truck and high pressure cylinder 55 with the valve gear associated therewith. Fig. 4 is an enlarged longitudinal sectional view of a valve gear of the Baker type with parts broken away. Figs. 5 and 6 are different cross-sections thereof with parts 60 broken away. Fig. 7 is a perspective view of a portion of the connecting means between the front and rear gears. Fig. 8 is a diagrammatical view of the front and rear valve gears and the connection therebetween 65 illustrating the invention, and Figs. 9 and 10 are charts produced by the high pressure and low pressure engines.

Referring to the drawings, A and B designate the respective high and low pressure 70 cylinders on one side of the locomotive of the Mallet type, and C and D the valve gears for the respective cylinders, which gears are connected together to operate in unison.

The valve gear C is carried by a gear 75 frame 1 suitably mounted at a side of the locomotive, as on the guide yoke 2 and embodies a reverse-yoke 3, which is of substantially inverted U-form, and has its legs journaled in the respective sides of the frame 1, 80 as at 4. A second yoke 5 is suspended within the reverse-yoke 3, having its leg ends provided with trunnions which are journaled in bearings 6 provided in the respective legs of the reverse-yoke near their inner ends. A 85 gear connecting rod 7, in the form of a lever, is pivotally carried intermediate its ends in vertical position by the lower end of the yoke 5, as at 8, and has its upper end pivoted to the horizontal arm of a bell-crank lever 90 9, which lever is fulcrumed at 10 to the gear frame 1 between the sides thereof. The lower end of the rod 7 is connected by an eccentric rod 11 to the crank-pin eccentric arm 12 of one of the drive wheels 13 of the 95 associated set. The vertical arm of the bell-crank 9 is connected at its lower end by a valve-rod 14 to a combination lever 15, which is fulcrumed to the valve stem cross-head 16 of the high pressure cylinder A 100

The lower end of the lever 15 is pivoted to a union link 17, which is in turn pivotally carried by the piston rod cross-head 18 of the cylinder A (Figs. 3 and 4).

5 It will be noted that the union link 17 is connected directly to the cross-head 18 instead of to an arm carried by and depending from the cross-head, as has heretofore been the practice. This not only eliminates one 10 part but quite materially lightens the cross-head, which is an important feature.

The forward valve gear D is approximately the same as the gear C except that one is reversed with respect to the other. In 15 the gear D, 1' designates the gear frame; 3' the reverse-yoke pivoted to the frame, as at 4'; 5' the second yoke pivoted to the reverse-yoke, as at 6'; 7' the gear connecting rod pivoted to the yoke 5', as at 8'; 9' the 20 bell-crank pivoted to the frame 1', as at 10'; 11' the eccentric rod; 14' the valve-rod; 15' the combination lever; 16' the valve stem cross-head, and 17' the union link.

With the exception of the manner of connecting the combination levers 15, 15' to the cross-heads 18, 18', the valve gears C and D illustrated are the well known Baker type and the construction and operation thereof need not, therefore, be more specifically described.

Intermediate the two trucks of the locomotive are mounted a pair of parallel rock-shafts 19 and 20, which extend from one side to the other of the locomotive transversely thereof. These shafts are caused to have like rocking movements in unison by reason of a link 21 having universal joint connection at its ends with respective arms 22 and 23 fixedly rising in parallel relation 35 from the shafts (Fig. 7). A vertical arm 24 at each end of the shaft 19 is connected at its free end by a reach-rod 25 to the upper end of the reverse-yoke 3 of the respective gear C. A similar arm 26 at each end of the 40 shaft 20 is connected by a reach-rod 27 to the upper end of the reverse-yoke 3' of the respective gear D. The purpose of providing the two shafts 19 and 20 and the universal connection therebetween is to allow for 45 the relative turning movements of the two trucks of the locomotive as it takes curves. If it was not for this the arms might all be mounted on one shaft, as both shafts are intended to have the same movements.

55 It is to be understood that the connection between the front and rear valve gears is the same as heretofore employed in connection with compound engines of the Mallet type employing valve gears of the Baker type, except that the arms 26 on the shaft 20 are 60 inclined forward at approximately a 45° angle to the arms 24 instead of being parallel or substantially parallel therewith, as has heretofore been the custom, and it is in this 65 slight difference in construction that the pri-

mary feature of the invention resides, as will be hereinafter more fully described.

The means illustrated, in the present instance, for controlling the movements of the shafts 19 and 20 and the reverse-yokes of 70 the respective valve gears comprises a rod 28, which is connected at one end to an arm 29 rising from the shaft 19 and has its other end connected to a piston, not shown, within a control cylinder 30 (Figs. 1 and 7). It is 75 evident that the admission of fluid under pressure to the cylinder 30 to control the movements of the rod 28 is under control of the engineer within the locomotive cab, as is well understood in the art. 80

Referring to Fig. 8, *a* and *a'* designate the full running positions of the reverse-yokes 3 and 3', respectively, for the valve gears C and D, and *b* and *b'* designate the mid-gear positions of the reverse-yokes for 85 the respective valve gears. It will be understood that for the higher speeds the reverse yokes 3 and 3' are usually placed at about the mid-gear positions *b* and *b'*, respectively, in which positions the low pressure 90 engine B has a considerably longer cut-off than the high pressure engine A, which is the most favorable condition for higher speeds. In starting, however, it is desirable to reverse this condition so that the 95 high pressure engine has the longer cut-off at full gear position. These reversed conditions are obtained by inclining the arms 26 on the shaft 20 at approximately an angle of 45° to the vertically disposed arms 100 24 on the shaft 19 and making the arms 26 slightly longer than the arms 24. By this arrangement it will be noted in Fig. 8 that when the reverse-yoke 3 is in its full gear position *a* the reverse-yoke 3' of the forward 105 valve gear D will be in its full gear position *a'*; and also that when the reverse-yoke 3 is moved to its mid-gear position *b* the reverse-yoke 3' will only have moved a portion of the distance to its mid-gear position *b'*. It 110 is apparent that when the reverse-yokes are in this position the high pressure engine A will have the longer cut-off and will therefore be the stronger of the two. This is illustrated by the ellipse diagrams shown 115 in Figs. 9 and 10, which are for the high and low pressure engines, respectively. In these diagrams the outer ellipses of the respective engines were taken when the valve 120 gears were set for starting or slow running, and the inner ellipses of the respective engines were taken when the valve gears were hooked up for high speed running. In the high pressure diagram (Fig. 9) the first vertical line, from left to right, indicates the preadmission and cut-off points, the second line indicates the release and closure points for a forward stroke of the piston, and the last two lines indicate the release 125 and closure points and the preadmission 130

and cut-off points for the back stroke of the piston. The low pressure diagram (Fig. 10) is the same in its reading as the high pressure diagram except that the forward stroke takes place at the right instead of at the left of the center vertical line. From the outer ellipses it will be noted that in starting, or for slow running, steam is admitted to the high pressure engine approximately between the points *c* and *c'*, the cut-off occurring at *c'*, while in the low pressure engine steam is admitted approximately between the points *d* and *d'*, the cut-off occurring at *d'*, thus showing that the high pressure engine, under such condition, has the longer cut-off of the two and is therefore the stronger. The inner ellipses of the two charts show that when the valve gears are hooked up for high speed running the cut-off of the high pressure engine takes place at approximately the point *e* and that the cut-off on the low pressure engine takes place at approximately the point *f*, thus showing that the low pressure engine carries steam the longest and is the stronger under high speed running conditions.

This arrangement does not in any way sacrifice the reversing or backing-up motion, as will be apparent from the diagram. The purpose of making the arms 26 longer than the arms 24 is to lengthen the arc of movement of the point of connection of the reach-rods 27 with the arms 26 and to effect a corresponding increase of the horizontal movement of such points of connection when the arms 26 are swung rearward from full running position.

It is apparent from the above that by advancing the arc of the low pressure reverse shaft arms 26 the rate of hooking up of the low pressure engine with respect to the high is retarded, giving for a starting condition considerably longer cut-off at full gear on the high pressure engine than on the low, with a reversed condition for the higher speeds or running position, in which the low pressure engine carries steam considerably longer than the high pressure. This improves the steam distribution by relieving the high pressure engine of back pressure at high speeds ranging from 10 to 50 miles an hour, and at the same time gives an ideal distribution of steam for starting purposes. If the valves are set to produce the same cut-offs on both engines at all reverse lever positions it is impossible on account of back pressure to obtain a speed of over 10 miles per hour.

The chart diagrams in Figs. 9 and 10 are shown in reversed positions due to the high pressure engine having an inside admission piston valve and the low pressure engine having an outside admission slide valve.

I wish it understood that my invention is not limited to any specific construction,

arrangement or form of the parts or to use in connection with any particular type of valve gear, as it is capable of numerous modifications and uses in different connections without departing from the spirit of the invention. 79

Having thus described my invention, what I claim as new, and desire to secure by Letters Patent, is—

1. The combination with a pair of valve gears, of a connecting mechanism therebetween including a pair of rocker arms one inclined with respect to the other and connected to rock in unison, and separate means connecting said arms to respective gears. 75

2. The combination with a pair of valve gears, of a connecting mechanism therebetween including a pair of relatively angled rocker arms, pivotally-jointed connection between said arms to cause them to 85 rock in unison, and separate means connecting said arms to respective gears.

3. The combination with a pair of valve gears, each having a reverse member, of a pair of connected relatively angled rocker arms adapted to rock in unison, and separate means connecting said arms to the reverse members of respective gears. 90

4. The combination with a pair of valve gears, each having a reverse member, of a pair of connected rocker arms, one at approximately a 45° angle to the other, adapted to rock in unison, and separate means connecting said arms to the reverse members of respective gears. 95

5. In a locomotive having connected high and low pressure engines, the combination with a valve gear for each engine, of mechanism connected to each of said gears and having a plurality of relatively angled rocker arms, the angled arms of the mechanism causing it when operated to impart different predetermined movements to said gears in unison to vary the relative periods of cut-off of the admission valves of the 110 engines. 100

6. The combination with a pair of valve gears, each having a reverse member, of a single means connecting said members, and having a plurality of relatively angled rocker arms for causing different adjustments to be imparted to said members when said means is moved. 115

7. In a locomotive having connected high and low pressure engines, the combination with a valve gear for each engine, of mechanism connected to each of said gears and operable to simultaneously adjust the same, said mechanism having a pair of relatively angled arms connected to respective gears 125 and adapted to cause the movement communicated to one gear by a movement of said mechanism to differ from that of the other gear, and means for moving said mechanism. 130

8. The combination with a pair of valve gears arranged one in advance of the other, of a connecting mechanism therebetween including a pair of rocker arms, one inclined 5 relative to the other and connected to rock in unison, and separate means connecting said arms to respective gears whereby one

gear is caused to have a differently timed valve cut-off from the other when the mechanism is moved.

10

In testimony whereof I have hereunto signed my name to this specification.

ROSS G. GRAHAM.
